UNITED STATES PATENT OFFICE

103,250

DESIGN FOR A DESK

Frank T. Parrish, Gardner, Mass., assignor to
Heywood-Wakefield Company, Boston, Mass., a
corporation of Massachusetts

Application January 7, 1937, Serial No. 66,937

Term of patent 7 years

To all whom it may concern:

Be it known that I, Frank T. Parrish, a citizen of the United States, residing at Gardner, in the county of Worcester and Commonwealth of Massachusetts, have invented a new, original, and ornamental Design for a Desk, of which the following is a specification, reference being had to the accompanying drawing, forming part thereof, in which

Fig. 1 is a perspective view of a desk showing my design.

Fig. 2 is an enlarged cross-sectional view on the lines 2—2 of Fig. 1.

As shown in the drawing, all four legs of the desk are of quarter-round section, and the out-

wardly faced convex surface of each leg is on substantially the same radius as and, therefore, flush with the corresponding lower rounded corner of the desk top; the latter's rounded-over edges at each corner merge with the convex surface of the associated leg, and along the sides with the flat surfaces of the boxing. Said boxing and also the bracing present exterior surfaces which merge and are flush with the edges of the convex surfaces of the legs, in the zones of juncture of said boxing and bracing with said legs.

I claim:

The ornamental design for a desk as shown and described.

FRANK T. PARRISH.
